Primary Examiner — Calvin E Vansant*Assistant Examiner* — Mark T. Philipps(74) *Attorney, Agent, or Firm* — Muncy, Geissler, Olds & Lowe, PC(57) **CLAIM**

The ornamental design for a sewing machine, as shown and described.

DESCRIPTION

FIG. 1 is a front elevational view of a sewing machine showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof; and,

FIG. 8 is another perspective view thereof.

The broken lines illustrate portions of the sewing machine which form no part of the claimed design.

1 Claim, 8 Drawing Sheets(56)
